HYDRAULIC TURBINES

Paul Dériaz, Rugby, England, assignor to The English Electric Company Limited, London, England, a British company

Application April 5, 1954, Serial No. 420,987

Claims priority, application Great Britain April 24, 1953

7 Claims. (Cl. 253—143)

The invention relates to hydraulic turbines. Such turbines of the fixed propeller type or of the feathering runner vane type which have a high specific speed are liable to attain runaway speeds in the order of magnitude up to three times and even more the normal speed within a few seconds after a complete relief from load when the speed governor is out of action. This would involve an increase in centrifugal stresses to about nine times or more the normal stresses at synchronous speed which might cause complete destruction or at least severe damage to the turbine and to the electric generator driven by the same, as well as to the building.

In order to limit the overspeed reached by a hydraulic turbine under the above conditions, hydraulic brake vanes have been used which are hinged to and normally retracted in the propeller body but which emerge therefrom when the centrifugal loads exceed a limit defined by some breaking link, and which then receive from the water vortex flowing to the propeller vanes a torque which is opposed to the torque applied to the latter whereby an effective limitation of the overspeed is attained.

Retaining the hydro-brake vanes in the retracted position until a predetermined overspeed condition is reached, and automatically retracting the said vanes when the speed has dropped to a considerably lower value, by means of springs, has also been proposed.

According to the present invention the hydro-brake vanes of a hydraulic vertical shaft turbine are made hollow and are partly filled with an easily movable inertia medium, for example a heavy liquid or small solid bodies, mercury being a typical example of a heavy fluid, and steel balls of small solid bodies. This medium, on the turbine reaching a predetermined overspeed condition, assembles by centrifugal force on the inwardly sloping inner face of the outer wall of the hollow hydro-brake vane and tilts the same into the operative position, in which the said medium assembles inside the tip of the hollow hydro-brake vane and retains the latter in its operative position, until the speed of rotation has dropped to a predetermined low value at which the said medium can flow by gravity to a position inside of the said pivot point, and tilt the hydro-brake vane back into the retracted position.

Preferably the braking torque opposite the driving torque on the propeller blades is produced by making the hydro-brake vanes box-shaped with a flange at one of its upstream edges only, for the deflection of the water vortex.

The hydro-brake vanes are preferably hinged each about an axle mounted in a separate segment of a hydro-brake ring, each such segment being individually attached to, and removable from, the turbine runner body.

In order that the invention may be clearly understood and readily carried into effect, an embodiment thereof will now be described by way of example with reference to the accompanying drawing, in which:

Fig. 1 is an axial part section of the runner of a hy-

2

draulic turbine showing a hydro-brake vane according to the invention,

Fig. 2 is a cross section along the line 2—2 of Fig. 1, and

Fig. 3 is a part plan view in section along the line 3—3 of Fig. 1.

Figs. 4 and 5 are part-sections corresponding to Figs. 1 and 3 respectively and showing the ends of the hollow hydro-brake vanes in a slight modifications.

The runner body 1 is attached to the vertical turbine shaft 2 and carries a number of hydro-brake ring segments 3 which are attached to it by screws 4 individually detachable. In each segment 3 an axle 5 is pivoted which is fixedly connected to a hollow hydro-brake vane 6 of box-shape (Fig. 2), having one edge, 6', chamfered and the other provided with a flange, 6'', whereby the deflection of the water vortex is effected in the projected position required for producing the braking torque. The outside wall 6''' of the hollow-brake vane slopes down inwardly at a moderate angle in the projected position (shown in full lines in Fig. 1) and at a very steep angle in the retracted position (shown in dotted lines).

Each vane 6 finds an abutment 3' on the upper part of the segment 3 in the retracted position, which is indicated in Fig. 1 in dotted lines, and an abutment 3'' on the lower part of the segment 3 in the projected (operative) position, which is shown in full lines.

A heavy liquid, for example mercury, occupies a small proportion of the hollow space inside the hydro-brake vane 6, and in the rest position assumes a free surface 7 indicated in Fig. 1 in dotted lines, where it is substantially below the pivot axis of the hydro-brake vane 6, and consequently does not produce any appreciable moment.

As the turbine rotates at ordinary speed, the medium assumes by centrifugal force a free surface 8 indicated in small dots in which it assembles on the inner face of the outside wall of the vane 6 below the pivot axis, and accordingly produces an anticlockwise moment tending to keep the vane 6 in the retracted position.

When the turbine assumes an overspeed condition, the medium climbs up the inner face of the outside wall 6''' of the vanes 6 by centrifugal action and assumes a free level 9 indicated in chain-dotted lines. In this position it produces a clockwise moment on the vane 6 tilting the same into the operative position, the said medium accumulates then at the hollow tip of the vane 6 and assumes a free surface 10 shown in a full line.

When, as a result of reinstating the normal speed governor operation, the speed of the turbine has dropped so far that the action of gravity overcomes that of centrifugal force on the said medium, the latter flows down the sloping inner face 6''' of the wall of vane 6 and assumes a free surface 11 as indicated in a double chain-dotted line, i. e. it accumulates at the opposite side of the pivot 5 and produces an anticlockwise moment on the vane 6, which tilts the same back into the retracted position.

The stops 3' and 3'', respectively, limit the tilting movement of the hydro-brake vane 6.

Instead of mercury another liquid of high density could be used, the quantity required being proportionally larger as the density is lower than of mercury.

Alternatively, as shown in Figs. 4 and 5 small and easily movable solid bodies 10', for example steel balls as used for ball bearings, or shot, could be used, which for the purposes of the present invention behave substantially alike to a liquid.

Adjustment of the steeply inclined sloping position of the inner surface 6'' in the retracted position of the vane 6 fixes the tripping speed at which the hydrobrake vanes come out, and of the moderately inclined sloping posi-

tion of the same surface 6" at the projected position determines the speed at which the said hydro-brake vanes automatically retract.

What I claim as my invention and desire to secure by Letters Patent is:

1. A hydraulic vertical shaft turbine comprising in combination: a runner, runner vanes attached to the said runner, hollow hydro-brake vanes, pivot pins articulating the said hydro-brake vanes to the said runner, and an easily movable inertia medium partly filling the said hollow hydro-brake vanes, each of the said vanes having an outside wall sloping inwardly at a very steep angle in a normal working position in which the said medium assumes a position below the pivot pin of the hydro-brake vanes and keeps the same retracted in the said runner, an overspeed condition in which the said medium rises along the said steeply sloping wall above the said pivot pin and tilts the said hydro-brake vane out of the said runner into the water vortex; a braking position in which the said medium accumulates in the hollow tip of the hydro-brake vane and keeps it in the tilted position, and a restoring position in which the said outer wall slopes inwardly at a moderate angle in which the said medium upon reduction of speed flows from the said hollow tip along said wall to a position inside of the said pivot, restoring the said hydro-brake vane to its said normal working position.

2. A hydraulic turbine as claimed in claim 1, wherein the said inertia medium is mercury.

3. A hydraulic turbine as claimed in claim 1, wherein the said inertia medium consists of small balls of a heavy metal.

4. A hydraulic turbine as claimed in claim 1, wherein the said hollow hydro-brake vanes are box-shaped and have a flange at one upstream edge only for the asymmetrical deflection of the water vortex in the said braking position.

5. A hydraulic turbine as claimed in claim 4, wherein the upstream edge of the said hollow hydro-brake vane opposite the said flange is chamfered.

6. A hydraulic vertical shaft turbine comprising in combination: a runner, runner vanes attached to the said runner, hollow segments individually attached removably to the said runner and forming a segment ring, a

5 pivot pin attached in each of the said segments, a hollow hydro-brake-vane-pivoted on each of the said pivot pins; and an easily movable inertia medium partly filling the said hollow hydro-brake vanes, each of the said vanes having an outside wall sloping inwardly at a very steep angle in a normal working position in which the said medium assumes a position below the pivot pin of the hydro-brake vanes and keeps the same retracted in the said runner, an overspeed condition in which the said medium rises along the said steeply sloping wall above the said pivot pin and tilts the said hydro-brake vane out of the said runner into the water vortex, a braking position in which the said medium accumulates in the hollow tip of the hydro-brake-vane and keeps it in the tilted position, and a restoring position in which the said outer wall slopes inwardly at a moderate angle in which the said medium upon reduction of speed flows from the said hollow tip along said wall to a position inside of the said pivot, restoring the said hydro-brake vane to its said normal working position.

7. A hydraulic vertical shaft turbine comprising in combination: a runner, runner vanes attached to the said runner, hollow hydro-brake vanes, pivot pins articulating the said hydro-brake vanes to the said runner arranged tangentially to a pitch circle, and an easily movable inertia medium partly filling the said hollow hydro-brake vanes, each of the said vanes having an outer wall running in the retracted position of the said vane outside the said pitch circle with its inner wall surface sloping inwardly at a very steep angle, and a pocket at the lower end of said outer wall containing the said inertia medium at the rest and low speed of the said runner, the said pocket lying in the extended position of the said vanes inside the said pitch circle and in the retracted position of the said vanes outside the said pitch circle.
